UNITED STATES PATENT OFFICE

2,006,446

MEANS FOR ADJUSTING CONTAINER BOTTOMS

Bruce J. Davidson, Kew Gardens, N. Y., assignor
to National Biscuit Company, New York, N. Y.,
a corporation of New Jersey

Application November 12, 1932, Serial No. 642,358

16 Claims. (Cl. 206—44)

This invention relates to improvements in means for adjusting container bottoms.

Many kinds of merchandise such as crackers, cookies, biscuit, and the like are sold from the containers or boxes in which they are shipped, the merchants being provided with glass front display covers which take the place of the covers that are on the boxes during shipment. The containers have four short flanges or flaps at the top which are turned inward over the goods when packed, but three of which are turned or bent outward against the sides of the box and the frame of the cover slipped over them after the box is opened. The frame has a number of lugs or projections that engage under the lower edges of the flanges to hold the frame in position on the box. The glass cover is hinged to this metal frame and can be raised to afford access to the contents. A cover of this type that is largely used is shown in the patent to Taylor, No. 1,694,024, December 4, 1928. As the goods are sold, those remaining in the carton are not well displayed through the glass cover because they are too low in the box. In order to keep the goods close to the glass cover where they will be effectively displayed, means have heretofore been provided for adjusting the bottom of the container so as to bring the goods closer to the top. Such means are disclosed in my copending applications, Ser. Nos. 617,300, filed June 15, 1932, and 642,356 filed November 12, 1932.

At the present time there are many millions of these glass front display covers in use and the present invention has for one of its objects to provide a means whereby these covers can be adapted to convenient use with adjustable bottoms for the containers. In some instances this is accomplished by bars or frames made from bars or rods which are detachably connected to or made to fit into the metal frames of the covers. These bars or bar frames are adapted to cooperate with flaps or extensions of the adjustable bottoms to hold them in any position of adjustment. In other forms of the invention, the frame or bars are fixed to the cover frame, as by welding or soldering, and this form may of course be made as an integral part of new covers at the time of their manufacture, or added to existing covers. In all of these cases, or forms of the present invention, the means for adjusting the bottom of the container is accessible through the display cover, and the cover frame carries or is provided with means for supporting the bottom in different positions of adjustment.

When the merchandise is packed in the con-

tainer at the bakery, the adjustable bottom is placed therein with its flaps extending upwardly along two sides of the box. When the merchant receives the goods, he replaces the shipping cover with a glass front display cover into which he has slipped a supplemental frame or bars and the invention is ready for use. Of course, if the merchant has been provided with covers having the bars or rods permanently secured therein, it is only necessary for him to place the cover on the container. In either case, all adjustments of the bottom can be made without removing the display cover.

My invention may be embodied in many different forms, several of which are illustrated in the accompanying drawings wherein:

Fig. 1 is a cross section through a container and a display cover frame showing the adjustable bottom raised to about mid-position, the hinged glass cover being omitted from the cover frame.

Fig. 2 shows a metal cover frame, the glass cover being omitted.

Fig. 3 illustrates a carton that may be used with my invention.

Fig. 4 shows a frame made from metal bars, bent and welded together, adapted to fit in the cover frame of Fig. 2 and hold the bottom in adjusted position as shown in Fig. 1.

Fig. 5 shows the adjusted frame of Fig. 4 fitted into the cover frame of Fig. 2.

Fig. 6 is a blank for forming the adjustable bottom and side flaps.

Figs. 7 and 7—A show another form of adjusting frame and how it fits in the cover frame respectively.

Figs. 8, 8—A and 9, 9—A are similar views of other forms of adjusting frames.

Fig. 10 is a detail view of one corner of a container showing how the adjustable bottom is supported by the frames of Figs. 7 to 9.

Fig. 11 shows a frame having hinged side bars, and Figs. 11—A and 11—B show its use with the cover frame and adjustable bottom.

Figs. 12, 12—A, and 12—B are similar views wherein the adjusting frame has pivoted double side bars for locking the bottom in adjusted position.

Fig. 13 shows the several steps or stages in the operation of adjusting the bottom with frames such as shown in Figs. 4, 7, 8, 9, 14, and 15.

Figs. 14, 14—A show another form of frame and how it fits or "snaps" into the cover frame.

Fig. 15 shows two bars or rods which are fixedly

secured to the cover frame as shown in Fig. 15—A, by welding, soldering, or other means.

Figs. 16 and 17 are sectional views through the cover frame showing how the adjusting frame is supported.

In Figs. 1 to 6 I have illustrated a preferred form of my invention and how it may be used with existing display covers and cartons. The adjusting frame shown in Fig. 4 is generally rectangular in shape and three of its sides are formed from a single bar or rod 20, the ends of which are doubled upon themselves at 21, 22 so as to provide spaced parallel side bars 23, 24 on the two sides of the frame, the inner ends of the bars 24 being bent inwardly and welded at 25 to the side bars 23. The bar 20 is preferably a flat bar but it may be round or any other shape desired. The cross bar 26 is welded at 27, 27 to the bars 23, 24, and its ends project beyond the side bars to provide lugs 28, 28 which engage under the flanges 29, 29 of the display cover frame 30 to hold the adjusting frame in position.

The cover frame 30, shown in Fig. 2, is of the type commonly used in the baking industry, and as shown in the patent to Taylor, No. 1,694,024, above referred to. The cover frame 30 is made from sheet metal such as brass, the metal being folded to provide inwardly projecting ledges 31, 31 at the top and bottom of the cover, and upwardly extending lips 32, 32 at the two sides of the frame. As shown in the Taylor patent just referred to, the glass cover is hinged adjacent one of the lips 32, 32, but has been omitted from the present drawings because it forms no part of the invention. It will, however, be understood that the hinged cover closes down over the lips 32, 32 to close the opening in the frame 30.

In Fig. 3, I have shown a carton 33 of the type usually used for packing bakery goods, and which has three downwardly turned flanges 34 at its top, only one of which shows in Fig. 3, and an inwardly turned flange 35. The frame 30 of the display cover fits down over these flanges 34 and is held in position by engagement with the lower edges of the flanges 34, as is well understood in the art.

The adjusting frame of Fig. 4 is designed to fit in the cover frame 30, the lugs 28 being below or lying in a plane beneath the plane of the side bars 23, 24 so that they can pass under the flanges 29, 29 and the ends of the side bars will rest on the ledges 31, the position of the adjusting frame in the display cover frame being clearly shown in Fig. 5.

In Fig. 6 I have shown a blank for forming an adjustable bottom and its side flaps which may be used with my present invention, but I may also use the form of blank shown in my earlier copending applications. In the present Fig. 6, the blank is scored to outline a bottom 36 and stiffening side flanges 37, 37 and end flaps 38, 38. In using this blank, it is folded along the score lines 39 and placed in the bottom of the container with the flanges 37 and flaps 38 extending upwardly and lying close to the sides of the container. The container is then filled with merchandise and when it is received by the merchant, he takes off the shipping cover and replaces it with the display cover 30, in which he has placed the adjusting frame 20. As shown in Figs. 1, 10, and 13 the side bars 24 are over the ends of the flaps 38, 38. After a part of the merchandise has been sold, he will reach through the cover opening and fold outwardly the ends of the two flaps on the proper score lines, and

then grasping the folded ends, will raise the bottom 36 to such a height that the folded ends can be tucked down between the respective side bars 23, 24 as shown in Fig. 1, which holds the bottom 36 in adjusted position.

The folds in the flaps will of course be made at such a point that the bottom 36 will come to rest at the proper height when the ends of the flaps are tucked down between the side bars 23, 24. The material of the flaps is of sufficient stiffness and the bars 23, 24 close enough together so as to prevent the flaps from straightening out and releasing the bottom.

The bottom may be adjusted as many times as desired or necessary to keep the goods close to the top so that they may be properly displayed, as shown in Fig. 13—A, 13—B, 13—C, and 13—D.

In Figs. 7 to 10, I have shown three modified forms of the invention in which the adjustable frame has single side bars and the upwardly extending lips on the display frame may serve the function of the outer side bars 23 in the form of the invention shown in Fig. 4.

In Fig. 7 the frame is formed from a single strip of metal 40 which forms three sides of a rectangular frame, the two sides 41, 41 being offset inwardly at 42, 43 and connected by a cross bar 44, welded thereto, and the ends of which project laterally to provide lugs 45, 45 to engage under the flanges 29 of the display cover frame 30.

In Fig. 8 I have shown an adjusting frame 46 made from a single rod or wire bent into shape, and its ends welded together so as to provide two end bars 47, 47 and side bars 48, 48, the metal being bent so as to provide lugs 49, 49 which project laterally from the bars 48 and lie in a plane beneath the main body of the frame. When the adjusting frame is in use, it fits into the cover frame 30, as shown in Fig. 8—A, with the lugs 49 engaged beneath the flanges 29 of the cover, 40 and the end bars 47 resting on the ledges 31.

In Fig. 9 I have shown the adjusting frame made from a single wire or rod 50, one end of the frame being left open. This rod is bent to form the lugs 51, 51, inset side bars 52, 52 and an end bar 53. The loops 54 in the rods at the open end are adapted to rest on one of the ledges 31 of the cover frame, and the lugs 51 engage under flanges 29 while at the opposite end the corners 55 rest upon the other ledge 31, the mid-portion of the end section 53 being bent inwardly and downwardly so that an offset 56 engages under the ledge 31.

In each of Figs. 7, 8, and 9, the side bars are offset inwardly so that when they are fitted into their respective frames, as shown in Figs. 7—A, 8—A, and 9—A, there will be a space or slot 57 between the respective side bars and the adjacent lips 32. This provides a space through which the free ends of the flaps 38 are tucked when the adjustable bottom is raised, as clearly shown in Fig. 10.

In the adjusting device shown in Figs. 1 to 10, the bottoms are held in adjustable position merely by the stiffness of the free ends of the side flaps and the friction between them and the side bars, but in the adjusting devices shown in Figs. 11 to 12—B, I have shown means for more securely locking the flaps in adjusted position. In Fig. 11 the adjusting frame consists of side bars 58 to which are welded cross bars 59 having laterally extending lugs 60 to engage under the flanges 29 of the cover 30. Auxiliary side bars or locking bars 61, 61 are hinged to one of the cross bars 59, as shown at 62, and at their oppo-

site ends, are bent to form latches 63 which engage with the other cross bar 59. This adjusting frame fits in the cover frame, as clearly shown in Fig. 11—A, with the ends of the side bars 58 resting on the ledges 31 and the ends 60 of the cross bars engaging under the flanges 29. The cross bars and side bars 59, 58 may be made from round stock or of any other cross sectional shape desired, but the locking bars 61 preferably are made from square material so as to provide a relatively sharp edge for tearing off the projecting ends of the flaps 38 when the bottom is adjusted, as shown in Fig. 11—B. As shown in Fig. 11—B, when it is desired to adjust the bottom 36 to a higher position, the flaps 38 are drawn up on the outside of bars 58, the locking bars 61 having first been raised to vertical position. The flaps 38 are then bent inwardly over the bars 58 and the locking bars 61 then swung down into horizontal position until the latches 63 engage on the cross bar 59. The free ends of the flaps 38 which then project down beyond the locking bars may be torn off, as indicated in the upper left hand part of Fig. 11—B. The locking bars 61 fit closely enough to the side bars 58 so that the flaps are securely held in adjusted position regardless of the weight of the material that may be supported by the bottom 36.

In Figs. 12 to 12—B I have shown an adjusting frame having a turn-over locking device. In this frame the cross bars 64 and side bars 65 are preferably formed from a single piece of material, welded together, and the side bars 65 are offset below the cross bars 64 so that they will engage under the cover flanges 29 and the cross bars will rest on the ledges 31. The turn-over locking means consists of two bars 66, 67, welded together to provide a space between them, the bar 67 being offset and its two ends pivotally mounted in loops 68, 69 formed in the cross rods 64. The loops 68, 69 may be open on their under sides, but the locking bars 66, 67 will be held in position because the cross bars 64 rest upon the ledges 31, which prevents the locking bars from dropping out.

In using this form of my invention, the locking bars are normally turned to the position shown at the right in Figs. 12 and 12—A, but when it is desired to adjust the bottom the locks are turned inwardly, as shown at the left in Figs. 12 and 12—A, and the adjusting flaps 38 are pulled up between the bars 66, 67 until the bottom reaches the desired height. The lock is then turned upwardly and outwardly on its pivotal connection 68, 69 until it assumes the position shown at the right in Fig. 12—B, which puts a sharp fold in the flap 38 and securely locks it in position. Any excess part of the flap may then be torn off.

In Figs. 14 and 14—A, I have shown another form of adjusting frame in which three sides of the frame are formed from a flat bar 70, which is bent to provide an end bar 71 and two side bars 72, which are offset inwardly similar to the side bars shown in Figs. 7, 8, and 9, and at their open ends are connected by a rod or wire 73, which is welded to side bars near their free ends at 74, 76, and running parallel to, but below and outside of, the side bars 72, is welded to them at the points where they join the end bar 71, as indicated at 75. These side portions 76, 76 of this wire engage under the flanges 29 of the cover, and intermediate its ends the portion 73 is bent upwardly and outwardly to form a projection 77 adapted to rest on one of the ledges 31, as clearly shown in Fig. 14—A.

When this adjusting frame is used, its side bar 72 will be spaced a slight distance from the lips 32 so as to provide a space through which the free ends of the flaps may be tucked, just as is the case in Figs. 7 to 10.

In Figs. 15 and 15—A, the adjusting frame comprises two offset bars 78, 78, the ends 79 of which are fixedly secured, as by soldering or welding, to the display cover frame 30, the offset portions of the bars providing spaces 80 between them and the lips 32, within which the ends of the flaps can be tucked. This is probably the most simple form of my invention and that which will be used as new display covers are made, but the forms heretofore described are adapted to be used with existing display covers, many millions of which are now in the hands of dealers.

Referring now to Fig. 13, I have illustrated the steps that will be used in changing the position of the adjustable bottom from time to time. In 20 this figure, A shows that the bottom 36 has been raised and secured in position, the flap 38 having been tucked down between the side bar of the adjusting frame and the lip 32 of the cover. In Fig. 13B I have shown the flap and bottom 38 25 raised a little higher, and in Fig. 13C the next step is shown wherein the flap 38 has been folded along one of its score lines and is ready to be pushed down between the side bar and lip 32. In Fig. 13D, the flap has been let down until the 30 new fold that was made in it engages the side bar of the adjusting frame and the bottom 36 has come to rest at a higher position of adjustment than it occupied in Fig. 13A. In this manner, the bottom may be adjusted as many times and 35 to any position desired.

I have shown and described several embodiments of my invention adapted for use with cartons and display covers that are commonly used with bakery products. However, it is to be understood that my invention is not limited either to the embodiments or uses shown but is capable of many other adaptations and uses with many kinds of merchandise, boxes, and containers, and I claim as my invention all forms, modifications 45 and equivalents thereof that come within the scope of my claims.

What I claim is:

1. In combination, a container having an adjustable bottom with side flaps extending upwardly therefrom, a cover frame fitting the top of the container and forming a cover opening therefor, side bars carried by said frame and spaced from the edges of the cover opening, said bars and flaps being arranged so that said flaps 55 may be raised through said opening and hooked over said side bars to adjust the position of said bottom.

2. In combination, a container having an adjustable bottom with side flaps extending upwardly therefrom, a cover frame fitting the top of the container and forming a cover opening therefor, said frame having upwardly extending lips adjacent said opening, side bars carried by said frame and spaced adjacent said lips, said 65 bars and flaps being arranged so that the flaps may be raised and tucked between said bars and lips to adjust the position of said bottom.

3. In combination, a container having an adjustable bottom with side flaps extending upwardly therefrom, a cover frame fitting the top of the container and forming a cover opening therefor, pairs of parallel side bars at opposite sides of said cover frame and adjacent said opening, said parallel bars and side flaps being so ar- 75

ranged that said flaps may be raised and their ends tucked between the bars of each pair to adjust said bottom.

4. In combination, a container having an adjustable bottom with side flaps extending upwardly therefrom, a cover frame fitting the top of the container and forming a rectangular cover opening therefor, said frame having ledges projecting inwardly on two sides of said cover opening, side bars supported on said ledges and lying adjacent the other two sides of said cover opening, said flaps being arranged to be raised and hooked over said bars to adjust said bottom.

5. In combination, a container having an adjustable bottom with side flaps extending upwardly therefrom, a cover frame fitting the top of the container and forming a cover opening therefor, said frame having inwardly projecting ledges and upwardly extending lips adjacent said opening, side bars supported on said ledges and lying adjacent said lips said flaps being arranged to be raised adjacent said bars and their ends tucked between said bars and lips to adjust the bottom.

25 6. As a new article of manufacture, a combination display cover and bottom adjuster for containers having adjustable bottoms comprising, a display cover frame having a cover opening therein, bars supported by said frame and spaced inwardly from two sides of said opening and accessible therethrough.

7. As a new article of manufacture, a combination display cover and bottom adjuster for containers having adjustable bottoms comprising, a display cover frame providing a cover opening, an adjuster frame mounted on said cover frame and having side bars spaced inwardly from two opposite edges of said opening.

40 8. As a new article of manufacture, an adjuster frame for a commercial display cover having a display opening and ledges adjacent thereto, said frame comprising a rectangular frame adapted to be inserted in said display opening, outwardly extending side lugs disposed adjacent the ends of two opposite sides and below the plane of the frame and adapted to engage under said ledges.

50 9. As a new article of manufacture, an adjuster frame adapted to fit in the frame of the usual display covers and comprising a generally rectangular frame, two opposite side bars of said frame being inset, and side lugs projecting laterally therefrom and in a different plane.

55 10. As a new article of manufacture, an adjuster frame for containers having adjustable bottoms comprising, a rectangular frame, three sides

of said frame lying in substantially the same plane, and the fourth side lying in another plane and secured to two opposite sides, said fourth side having projections extending beyond the two opposite sides to which it is secured to provide a pair of lugs, and said two sides projecting beyond said fourth side to provide a second pair of lugs lying in a different plane from said first mentioned pair of lugs.

5 11. As a new article of manufacture, an adjuster frame for containers having adjustable bottoms comprising, a frame having three sides formed from a single bar, two opposite sides of which are inset, the fourth side of the frame being formed from a bar secured to said inset sides 15 and extending therebeyond to provide lugs.

12. As a new article of manufacture, an adjuster frame for containers having adjustable bottoms comprising, a frame having three sides formed from a single bar, the two opposite sides 20 being folded upon themselves to provide double side rods, the inner rods being spaced from the outer, and a cross bar secured to the under side of said double side rods and projecting therebeyond to provide locking lugs.

25 13. As a new article of manufacture, an adjuster frame for containers having adjustable bottoms comprising, a rectangular frame, two opposite sides thereof having spaced parallel bars, and side lugs extending therefrom in a different 30 plane.

14. In combination, a container having an adjustable bottom with side flaps extending upwardly therefrom, a cover frame fitting the top of the container and forming a cover opening 35 therefor, pairs of parallel bars supported by said frame adjacent opposite sides of said opening, said bars and flaps being arranged so that said flaps may be raised within said opening and their ends tucked downwardly between the bars of each 40 pair to adjust said bottom.

15. As a new article of manufacture an adjuster frame for containers having adjustable bottoms comprising, a rectangular frame having side bars and cross bars, and locking bars pivoted 45 with respect to said cross bars and disposed adjacent said side bars in locking position.

16. As a new article of manufacture, an adjuster frame for containers having adjustable bottoms comprising, a rectangular frame having 50 side bars and cross bars, double locking bars pivoted to said cross bars and adapted to receive and lock the flaps of an adjustable bottom.
